UNITED STATES PATENT OFFICE.

WILLIAM A. STEWART, OF DETROIT, MICHIGAN.

WRENCH.

SPECIFICATION forming part of Letters Patent No. 761,110, dated May 31, 1904.

Application filed July 11, 1903. Serial No. 165,175. (No model.)

To all whom it may concern:

Be it known that I, WILLIAM A. STEWART, a citizen of the United States, residing at Detroit, in the county of Wayne and State of Michigan, have invented a new and useful 5 Wrench, of which the following is a specification.

My invention is an improvement in wrenches, having for its object a wrench 10 adapted for heavy work of all descriptions and also having for its object new means for locking the sliding jaw in position with reference to the stationary jaw.

My invention consists in the novel features 15 of construction and combination of parts described hereinafter, particularly pointed out in the claims, and shown in the accompanying drawings, in which—

Figure 1 is a perspective view of my wrench. 20 Fig. 2 is a side elevation, the movable jaw being in section and the handle broken away. Fig. 3 is a transverse section on the line 3—3 of Fig. 2. Fig. 4 is a detail perspective view of the movable jaw. Fig. 5 is a plan view of 25 the under side of the pawl.

In the drawings, A represents the usual 30 bar-handle, terminating at one end in a stationary jaw A', the upper portion of said jaw having its inner face offset, as at A². The bar A has a smooth upper surface adjacent the jaw A', and to the rear of this smooth portion forwardly-projecting rack-teeth A³ are formed. Sliding on this bar and over the teeth is a 35 movable jaw B. This jaw is shown in detail in Fig. 4 and has the central opening B'. Projecting rearwardly from the jaw is an integral 40 arm B², the upper surface of which is flush with the bottom of the opening B'. Projecting rearwardly from the jaw above the opening is a short arm B³, terminating in perforated lugs B⁴, the perforations of the lugs registering. A pawl C is formed with a central 45 forwardly-extending lug C', also perforated. This lug fits between the lugs B⁴, and a pintle B⁵ pivotally secures the pawl to the short arm B³, the length of the pawl plus the short arm being equal to the length of the long arm B².

A longitudinal groove B⁶ is formed on the under side of the short arm, and a similar 50 groove C² is formed on the under side of the

pawl. Teeth C³, adapted to coact with the teeth A³, are formed on the pawl on each side of the groove C². A spring-plate D is arranged in these grooves extending under both of the short arm and the pawl and being secured by 55 a countersunk screw D' to the short arm, the free end of the spring being adapted to lift the pawl out of engagement with the teeth A³.

Pivottally secured to the sides of the pawl adjacent its rear end are the free ends of an 60 open rectangular clip E, the frame of said clip inclosing the bar and long arm, as shown in Fig. 1, the horizontal member of said frame or clip lying when the pawl is in engagement with the teeth A³ some distance below the 65 long arm, permitting vertical movement of the clip when the spring lifts the pawl. A set-screw E' works in a threaded perforation formed in a boss E² on the horizontal member of the clip, the upper end of the screw engaging 70 a socket on the under side of the long arm.

The operation of my wrench will be readily understood. By turning the set-screw in one direction the clip will be drawn downward, clamping the pawl into engagement with the 75 teeth A³; but by turning the screw in the opposite direction the spring D will be given play and will lift the pawl out of engagement with the teeth A³ and the jaw B can slide along the bar. The offset face A² permits use of 80 the wrench on nuts of two sizes with one adjustment.

Having thus fully described my invention, what I claim as new, and desire to secure by 85 Letters Patent, is—

1. A wrench comprising a bar having a stationary jaw, thereon, teeth formed on said bar, a movable jaw sliding on the bar, a pawl pivoted to the rear of the movable jaw, a spring secured to said jaw and extending beneath the pawl, and adapted to lift the pawl, and means for locking the pawl in engagement with the teeth of the bar.

2. A wrench comprising a bar carrying a stationary jaw and having a toothed portion, 95 a movable jaw sliding on the bar, said jaw having a central opening and integral, rearwardly-projecting arms above and below the opening, the lower arm being the longer, the shorter arm having a longitudinal groove 100

formed therein, a pawl pivoted to the shorter arm and having a corresponding groove, a spring secured in the groove of the short arm and extending into the groove of the pawl, a 5 clip pivoted to the pawl and a set-screw working in said clip and bearing on the under side of the bar.

3. A wrench comprising a bar having a stationary head at one end thereof, said head 10 having a portion of its inner face offset, a movable jaw sliding on the bar, teeth formed

on said bar, a pawl pivoted to the rear of said head and engaging the teeth, a spring adapted to disengage the pawl, a clip pivoted at its free ends to the pawl, and a set-screw working in the clip and engaging the under side of the movable jaw. 15

WILLIAM A. STEWART.
